Application November 17, 1944, Serial No. 563,834

15 Claims. (Cl. 261—39)

1

The present invention relates to carburetors for internal combustion engines, and particularly to apparatus for correcting the operation of carburetors and other fluid flow measuring devices for variations in the pressure and temperature of the fluid being measured.

A carburetor for an internal combustion engine is required to maintain a controlled proportional relationship between the rate of flow of air to the engine and the rate of flow of fuel to the engine. In other words, the carburetor must control the fuel-to-air ratio. Since the fuels commonly used are of relatively constant density, while the density of the air varies with its pressure and temperature, it is necessary that the carburetor include a device which compensates its action for variations in air temperature and pressure. It is common to use a flexible bellows filled with a fluid having an appreciable temperature coefficient of expansion for that purpose. Since it is required that the bellows should not obstruct and thereby reduce the capacity of the air induction system, such bellows are commonly mounted in a chamber spaced from the air passage, and maintained in communication with the air passage by a branch air conduit of relatively small cross-sectional area.

It has been found that when such a bellows is mounted in a chamber so constructed and connected to the main air passage, that the temperature of the air in the chamber tends to become heated to a higher temperature than the air in the intake passage. The reason for this is that the carburetor body and the housing enclosing the bellows are usually formed of metal, and are so placed that they are exposed to heat from the engine. The air in the chamber takes up heat from the carburetor body and the walls of the chamber, and its temperature therefore increases. This causes the temperature responsive bellows to give a false indication of the temperature of the air entering the carburetor. This false indication is in a sense to indicate that the entering air is hotter and therefore less dense than is actually the case. The false indication given by the bellows causes the carburetor to cut down the fuel supply in proportion to the smaller mass of air flowing per unit time as indicated by the bellows, thereby causing the fuel-to-air ratio to be decreased. Because of the undesired leanliness of the mixture supplied to the engine under those conditions, the engine tends to heat up and to detonate.

It is, therefore, an object of the present inven-

tion to provide a device responsive to the pressure and temperature of the air entering an internal combustion engine, which does not obstruct the air induction passage and which is not adversely affected by ambient temperature conditions.

Another object of this invention is to provide a device which responds to the pressure at a first location and to the temperature at a second location spaced from said first location.

A further object of the present invention is to provide improved apparatus for measuring the rate of flow of a fluid of variable density. A still further object is to provide such a device including improved means for correcting the operation of the device for variations in the pressure and temperature of the fluid whose flow is being measured.

Other objects and advantages of the present invention will become apparent from a consideration of the appended specification, claims and drawing, in which

Figure 1 is a somewhat diagrammatic illustration of a carburetor for an internal combustion engine embodying the principles of my invention.

Figure 2 is a cross-sectional view of a portion of a carburetor showing a pressure and temperature responsive device built in accordance with the principles of the present invention.

Figure 3 is a cross-sectional view taken along the line 3—3 of Figure 2, showing a portion of the supporting structure of the temperature responsive device.

Figure 4 is a cross-sectional view of a different form of supporting structure for the temperature responsive device, and

Figure 5 is a cross-sectional view taken along the line 5—5 of Figure 4, looking in the direction of the arrows.

40

Figure 1

Referring to the drawing, there is shown a body 10 of a carburetor for an aircraft type internal combustion engine. Air enters the carburetor body 10 at an inlet 12 and flows thru a Venturi restriction 14 and a passage 15, past a throttle 16 and a fuel discharge nozzle 18 to an outlet 20. A supercharger may be provided between the outlet 20 and the intake manifold of the engine. In certain cases the supercharger may be upstream from the inlet 12, or two superchargers may be used, one in each place.

The Venturi restriction 14 produces a pressure differential between the inlet 12 and the throat of the restriction which varies substantially in

accordance with the square of the velocity of the air passing thru the restriction. Since the cross-sectional area of the venturi is constant, this pressure differential may be taken as a measure of the volume of air flowing thru the passage per unit time.

In order to obtain a pressure differential varying as a function of the mass of air per unit time flowing thru the venturi 14, the pressure differential between entrance 12 and the throat of venturi 14 is utilized to create an air flow thru a secondary air passage extending from entrance 12 to the throat of venturi 14. A plurality of impact tubes 22 are provided, whose open ends project into the entrance 12 to receive the impact of the entering air. The secondary air passage may be traced from entrance 12, thru tubes 22, a passage 24 interconnecting the impact tubes, a conduit 26, a chamber 28 in a pressure meter generally indicated at 30, a restriction 32, a chamber 34 in the pressure meter 30, a conduit 36, past a valve 38 into a chamber 40, and thru a conduit 42 to the throat of venturi 14. The valve 38 is operated by an expandible bellows 44.

The bellows 44 is filled with a fluid having a substantially zero coefficient of thermal expansion. For example, I may use a hydraulic fluid corresponding to Army Air Forces Specification 3580-D, Grade M. Alternatively, normal methyl aniline may be used. The interior of the bellows 44 is connected thru a conduit 43 to the interior of a rigid tube or bulb 47, which is mounted to extend transversely of the entrance to the air passage thru the carburetor. The liquid in the bellows 44 extends upwardly in the tube 43 to a point substantially above the level of the highest point in bellows 44. The bulb 47 is filled with a fluid, preferably a gas, having a substantially lower specific gravity than the liquid filling the bellows 44. The fluid in bulb 47 should have a relatively high coefficient of thermal expansion. By way of example, I prefer to use nitrogen in the bulb 47.

It may be seen that a change in the pressure adjacent bellows 44 causes an expansion or contraction of the bellows 44, resulting in a raising or lowering of the level of the liquid in the tube 43. Since the liquid in bellows 44 is insensitive to temperature changes, the position of valve 38 is not affected by changes in the temperature in chamber 40. However, variations in temperature at the air entrance 12 produces changes in the volume of the fluid in the bulb 47, which changes are transmitted thru the tube 43 to the interior of bellows 44, where they cause expansion and contraction of the bellows.

Since the air in the chamber 40 enters that chamber after passing thru an elongated and somewhat tortuous passage of relatively small cross-sectional area, the air picks up heat from the engine through the surrounding walls during its flow to the chamber 40 and enters the chamber 40 at a temperature substantially higher than that existing at the entrance 12. It is, therefore, essential that the valve 38 should respond to variations in the temperature at the air entrance 12 and not to variations in the temperature in the chamber 40, if accurate metering of the air flow is to be obtained.

In the secondary air passage, the pressure differential between the entrance 12 and the throat of venturi 14 is divided into two component pressure drops, one across the restriction 32 and the other across the valve 38. The valve 38 is positioned in accordance with the density of the air

flowing thru the passage 15. Valve 38 is moved toward open position as the air pressure increases and toward closed position as the air pressure decreases. If the volume of air flowing per unit time thru passage 15 remains constant while its density decreases, then the mass of air flowing is decreased, but the pressure differential set up by the venturi 14 remains constant. However, the movement of valve 38 toward closed position causes the component pressure drop across valve 38 to increase, and the component pressure drop across restriction 32 to decrease proportionately, reflecting the decrease in the mass of air flowing per unit time. By proper design of valve 38, the pressure drop across restriction 32 may be made to vary substantially in accordance with the mass of air flowing thru passage 15. This pressure differential across restriction 32 acts on a diaphragm 46 which separates the chambers 28 and 34. The force applied to diaphragm 46 is transmitted to a valve 48, on which it acts in a closing direction.

The fuel enters the carburetor from a fuel pump or other source of fuel under superatmospheric pressure. It flows thru a conduit 50, a valve 52 in a pressure regulator generally indicated at 54, a conduit 56, a mixture control unit generally indicated at 58, a jet system 60, past an idle valve 125, thru a conduit 62, a valve 64 in a second pressure regulator 66, and a conduit 68 to the fuel discharge nozzle 18.

The pressure regulator 54 includes a diaphragm 70 separating a pair of expandible chambers 72 and 74 and connected at its center to the valve 52. A spring 76 biases the valve 52 toward open position. A restriction 78 connects the chambers 72 and 74.

A portion of the fuel entering pressure regulator 54 flows thru chamber 74, restriction 78, chamber 72, a conduit 80, a chamber 82 in the pressure meter 30, past the valve 48, and thru a conduit 84 to the main air passage 15.

The pressure meter 30 includes a diaphragm 86 separating the chambers 34 and 82 and a diaphragm 88 separating the chamber 28 from a fourth expandible chamber 90. The valve 48 is biased toward closed position by a spring 92.

The chamber 90 is connected thru a conduit 94 to the fuel conduit 62 downstream from the jet system 60. The pressure in chamber 90 is therefore the same as that in the fuel line downstream from the jet system. The pressure in chamber 82 is the same as that in chamber 72 of pressure regulator 54.

The position of diaphragm 70 and valve 52 is determined by the balance between the pressure in chamber 74 acting in a valve closing direction and the spring 76 plus the pressure in chamber 72 acting in a valve opening direction. If the balance between these forces is upset, the diaphragm 70 and valve 52 move until the balance is restored. Therefore the pressure in chamber 72 is a measure of the pressure in chamber 74, which is substantially the same as the pressure

on the upstream side of the jet system 60. For any given constant cross-sectional area of the fuel passages thru the jet system 60, the pressure differential across it is a measure of the fuel flow thru it. This pressure differential, or rather a smaller pressure differential which is a measure of the pressure differential across the jet system, is applied thru the diaphragms 86 and 88 of pressure meter 30 to the valve 48, on which it acts in an opening direction.

From the foregoing, it may be seen that the

valve 48 is positioned in accordance with the balance between two forces, one of which varies in accordance with the mass of air entering the carburetor, and the other in accordance with the mass of fuel entering the carburetor. Furthermore, the valve 48 controls the mass of fuel entering the carburetor, since it controls the pressure in chamber 82. The pressure in the chamber 82 is transmitted to chamber 72 of pressure regulator 54 where it controls the position of valve 52 and hence the pressure on the upstream side of the jet system 60.

The pressure regulator 66 operates to maintain a substantially constant pressure on the downstream side of the jet system 60 and thereby to prevent variations in pressure at the fuel discharge nozzle 18, which may be due to operation of the throttle or to variations in engine speed, from reaching the downstream side of the jet system and affecting the fuel flow.

The pressure regulator 66 includes a pair of expandible chambers 96 and 98 separated by a flexible diaphragm 100, which is attached at its center to the valve 64. A spring 102 biases the valve 64 toward closed position. The chamber 96 is connected thru a conduit 104 to the conduit 26 and thence thru the passage 24 and impact tubes 22 to the air entrance 12. The chamber 98 is connected to the conduit 62.

The mixture control 58 includes a disc valve 106 fixed on a shaft 108. The disc valve 106 controls the flow of fuel thru ports opening into conduits 110 and 112 which lead into the jet system 60. When the disc 108 is in the position illustrated in full lines in the drawing, fuel can flow to the jet system only thru the conduit 110. This full line position of the disc valve 106 is known as the "lean" position of the mixture control 58. When the disc valve 106 is in the dotted line position shown in the drawing, the fuel can flow thru both the conduits 110 and 112. The dotted line position of disc valve 106 is termed the "rich" position of the mixture control. The disc valve 106 can also be moved to a "cut-off" position wherein it cuts off the flow thru both conduits 110 and 112.

The conduit 110 conducts fuel either thru a fixed restriction or jet 114, or thru a restriction 116 controlled by an enrichment valve 118 biased to closed position by a spring 120. The conduit 112 conducts fuel to a fixed restriction 122. Fuel flowing thru the restrictions 116 and 122 also flows thru another restriction 124 which limits the total flow thru restrictions 116 and 122.

The valve 118 is normally closed, but opens at 55 high pressure differentials across the jet system to increase the fuel-to-air ratio under heavy load conditions.

At low air flows, such as are encountered under idling conditions, the pressure differential set up by the venturi 14 tends to be erratic, and is not a reliable indication of the volume of air entering the engine. Provision is made to control the fuel flow directly in accordance with the throttle position at such times. The spring 92 in the pressure 60 meter 30 acts on valve 48 in a closing direction. When the differential pressure acting on diaphragm 46 is small, as under low air flow conditions, the spring 92 becomes the predominating force acting on valve 48. A closing movement of valve 48 causes an increase in the fuel flow thru the main fuel line, since the closure of valve 48 increases the pressure in chamber 82 of pressure 65 meter 30 and hence in chamber 72 of pressure regulator 54. Furthermore, the spring 76 of pres- 75

sure regulator 54 biases valve 52 in an opening or fuel flow increasing direction.

The idle valve 125 is pivotally attached to a lever 128, whose opposite end is connected by a link 130 to an arm 132 fixed on the shaft 134 of throttle 16. The idle valve is normally wide open when the throttle is beyond the range of positions near its closed position, usually termed the idling range. As the throttle moves into the idling range, thereby decreasing the air flow, the idle valve 125 moves toward closed position. At the same time, the springs 92 and 76 cause operation of valve 52 in an opening direction. The valve 52 is thereby opened sufficiently so that its restrictive effect on the fuel flow is less than that of the idle valve 125. Therefore the fuel flow under idling conditions is controlled primarily by the valve 125 in accordance with the position of the throttle, and not by the pressure meter 30 in accordance with the mass of air entering the engine.

Although I have illustrated a particular type of carburetor, it will be appreciated by those skilled in the art that my invention may be applied with equal facility to other types of carburetors. The carburetor illustrated may, for example, be modified by omitting the pressure regulator 54 and placing the valve 48 of the pressure meter 30 directly in the fuel line between the pump and the mixture control 58. If the carburetor is so modified, the valve 48 should be modified so that it is balanced against inlet pressure rather than discharge pressure, and so that it opens in a downward direction. The structure of valve 48 would then be similar to that of valve 52.

Figures 2 and 3

There is shown in Figure 2 a portion of the main body 150 of a carburetor, which may be of the rectangular type shown and described in my co-pending application Serial No. 406,776, filed August 14, 1941, and matured into U. S. Patent 2,361,993, issued November 7, 1944. This body 150 carries an end plate 152 which supports a plurality of parallel Venturi bars, one of which is shown at 154. A casing 156 is attached to the body 150 by any suitable means, such as bolts 158. The casing 156 is provided with a cover 160.

A shell 162 is enclosed within the casing 156 and a recess in the body 150. Inside the shell 162 is a flexible bellows 164. The space between the bellows 164 and the shell 162 is filled with a suitable fluid having a negligible thermal coefficient of expansion. The inner end of the bellows 164 is closed by a pair of cylindrical members 166 and 168. A spring 170 is retained between the cylindrical members 166 and 168 and the bottom of shell 162. The inner cylindrical member 168 carries at its center a cup 172 which cooperates with a guide 174 attached to the bottom of shell 162. The bottom of cup 172 abuts against a valve 176 which corresponds functionally to the valve 38 of Figure 1. The valve 176 cooperates with a port 178 formed in a seat member 180. The seat member 180 is provided with a threaded extension 182 at its left end, which cooperates with an adjusting nut 184 and a lock nut 186. The extension 182 is in threaded engagement with a cap 188, which is in turn threaded into the cover 160. The seat member 180 is hollow and is provided with ports 190 aligned with ports 192 in the cap 188, which are in fluid communication with a passage 194, which may be the same as conduit 36 of Figure 1.

The space between bellows 164 and shell 162

corresponds to the space inside bellows 44 of Figure 1. This space is connected thru a tube 196 to an elongated bulb 198 which is suspended across the entrance to the air passage by means of a pair of brackets 200, which are attached by bolts 202 to the end plates 152 of the carburetor body. The bulb 198 corresponds to the bulb 47 of Figure 1.

Figures 4 and 5

There is shown in Figures 4 and 5 a modified form of bulb supporting structure, which is designed to permit longitudinal expansion and contraction of the bulb without distorting the connecting tube or the supporting structure.

The bulb 250 of Figure 4 is an elongated metal tube having its ends sealed by plugs 252 and 254. The plug 252 is apertured to receive the connecting tube 256 which corresponds to the tube 43 of Figure 1 and the tube 196 of Figure 2. The plug 252 is also slotted, as at 260, to receive a transversely extending bolt 258. The bolt 258 is carried by two brackets 262 attached by any suitable means to a plate 264, which is bolted to the end plate 266 by bolts 268.

The plug 254 at the opposite end of bulb 250 is recessed to receive a pin 270 whose opposite end extends into a socket 272 in the end wall 266 of the carburetor. The plug 252, to which the tube 256 is attached, may be fixed in position by tightening the nut on the bolt 258. The tube 250 may then expand and contract freely. The resulting movements of the plug 254 will merely cause the pin 270 to move in and out of the socket 272. Therefore, any expansion or contraction due to temperature cannot place any strain on the various parts.

Altho, in the arrangements illustrated, the liquids of different thermal coefficients of expansion are kept separate by using containers at different levels and liquids of different specific gravities, it should be apparent that other equivalent arrangements could be used. For example, the two containers could be placed on the same level and a pressure-transmitting diaphragm placed in the line connecting them.

While I have shown and described preferred embodiments of my invention, other modifications thereof will readily occur to those skilled in the art, and I therefore intend my invention to be limited only by the appended claims.

I claim as my invention:

1. A carburetor for an internal combustion engine, comprising a main conduit for air flowing to said engine, means associated with said conduit for producing two unequal pressures whose difference is a measure of the velocity of air flowing thru said conduit, a secondary air conduit connecting two points in said main conduit subject to said two unequal pressures so that a flow of air is induced thru said secondary conduit by the difference of said pressures, a chamber forming a part of said secondary conduit and subject to heat from said engine, a pair of restrictions in series in said secondary conduit, valve means for varying the cross-sectional area of one of said restrictions, a flexible bellows in said chamber for operating said valve means, said bellows being expansible and contractible in accordance with pressure variations in said chamber and filled with a liquid having substantially zero coefficient of thermal expansion, a bulb having rigid walls and placed in said main air conduit above the uppermost part of said bellows, said bulb being filled with a fluid having a substantial coefficient of thermal expansion, a

passage connecting the interiors of said bulb and bellows so that the expansion of the fluid in said bulb tends to produce expansion of said bellows and thereby modifies the position of said valve and the air flow thru said secondary passage in accordance with the temperature in said main conduit, so that the pressure drop established across one of said restrictions is a function of the mass air flow in said main conduit, and means responsive to said pressure drop for controlling the flow of fuel to said engine proportional to said mass air flow.

2. A carburetor for an internal combustion engine, comprising a main conduit for air flowing to said engine, means associated with said conduit for producing two unequal pressures whose difference is a measure of the velocity of the air flowing thru said conduit, a secondary air conduit connecting two points in said main conduit subject to said two unequal pressures so that a flow of air is induced thru said secondary conduit by the difference of said pressures, said secondary conduit extending for a substantial portion of its length outside said main conduit pair of restrictions in series in said secondary conduit, where it is subject to heat from said engine, a chamber forming a part of said secondary conduit, a valve means for varying the cross-sectional area of one of said restrictions, a flexible bellows in said chamber for operating said valve means, said bellows being expansible and contractible in accordance with pressure variations in said chamber and filled with a liquid having substantially zero coefficient of thermal expansion so that its expansion and contraction are independent of the temperature in said secondary conduit, a bulb having rigid walls and placed in said main air conduit above the uppermost part of said bellows, said bulb being filled with a fluid having a substantial coefficient of thermal expansion and substantially less dense than said liquid, a passage connecting the interiors of said bulb and bellows so that the expansion of the fluid in said bulb tends to produce expansion of said bellows and thereby modifies the position of said valve and the air flow thru said secondary passage in accordance with the temperature in said main conduit, so that the pressure drop established across one of said restrictions is a function of the mass air flow in said main conduit, and means responsive to said pressure drop for controlling the flow of fuel to said engine proportional to said mass air flow.

3. In a carburetor for an internal combustion engine comprising, an air conduit, a chamber spaced from said conduit and subject to heat from said engine, a passage connecting said chamber and said conduit, means for measuring the mass air flow in said conduit including a valve to be operated in accordance with the temperature of the air in said conduit and the pressure of the air in said chamber, a flexible bellows in said chamber for operating said valve, said bellows being expansible and contractible in accordance with variations of air pressure in said conduit and filled with a liquid having substantially zero coefficient of thermal expansion, a bulb having rigid walls and placed in said main air conduit above the uppermost part of said bellows, said bulb being filled with a fluid having a substantial coefficient of thermal expansion and substantially less dense than liquid, a passage connecting the interiors of said bulb and bellows so that the expansion of the fluid in said bulb tends to produce expansion of said bellows and

thereby modifies the position of said valve in accordance with the temperature in said main conduit, and means responsive to said air flow measuring means for controlling the flow of fuel to said engine proportional to said mass air flow.

5 by modifies the position of said valve in accordance with the temperature in said main conduit, and means responsive to said air flow measuring means for controlling the flow of fuel to said engine proportional to said mass air flow.

4. A carburetor for an internal combustion engine, comprising a main conduit for air flowing to said engine, means associated with said conduit for producing two unequal pressures whose difference is a measure of the velocity of the air flowing thru said conduit, pressure differential responsive means for measuring air flow, a pair of branch conduits connecting said pressure differential responsive means to two points in said main conduit subject to said two unequal pressures, a chamber forming a part of one of said branch conduits, said chamber being spaced from said main conduit and having walls subject to heat from said engine, valve means for compensating the action of said pressure differential responsive means for variations in the pressure in said chamber and the temperature in said main conduit thereby rendering said pressure differential responsive means effective to measure the mass air flow in said conduit, a flexible bellows in said chamber for operating said valve means, said bellows being expansible and contractible in accordance with pressure variations in said chamber and filled with a liquid having substantially zero coefficient of thermal expansion so that its expansion and contraction are independent of the temperature in said chamber, a bulb having rigid walls and placed in said main air conduit above the uppermost part of said bellows, said bulb being filled with a fluid having a substantial coefficient of thermal expansion and substantially less than said liquid, a passage connecting the interiors of said bulb and bellows so that the expansion of the fluid in said bulb tends to produce expansion of said bellows and thereby modifies the position of said valve in accordance with the temperature in said main conduit, and means responsive to said pressure differential responsive means for controlling the flow of fuel to said engine proportional to said mass air flow.

5. A carburetor for an internal combustion engine, comprising: a conduit for combustion air flowing to said engine, means for measuring the mass flow of air thru said conduit including a valve to be operated in accordance with the variations of pressure and temperature of the air in said conduit, a flexible bellows for operating said valve, a chamber for containing said bellows spaced from said conduit so that said bellows will not restrict said conduit, said chamber being subject to heat from said engine, a passage connecting said chamber and said conduit, said chamber having walls subject to ambient temperatures different from the temperatures in said main conduit, said bellows being expansible and contractible in accordance with variations of air pressure in said conduit and filled with a first fluid having substantially zero coefficient of thermal expansion so that its expansion and contraction are independent of the temperature in said chamber, a bulb in said main air conduit and spaced vertically from said bellows, said bulb being filled with a second fluid having a substantial coefficient of thermal expansion and of different density than said first fluid and non-miscible therewith, a passage connecting the interiors of said bulb and bellows so that the expansion of the second fluid in said bulb tends to produce expansion of said bellows and there-

15 20 25 30 35 40 45 50 55 60 65 70

10

6. A carburetor for an internal combustion engine, comprising: a conduit for combustion air flowing to said engine, means for measuring the mass flow of air thru said conduit including a valve to be operated in accordance with the variations of pressure and temperature of the air in said conduit, a flexible bellows for operating said valve, a chamber for containing said bellows spaced from said conduit so that said bellows will not restrict said conduit, said chambers being subject to heat from said engine, a passage connecting said chamber and said conduit, said chamber having walls subject to ambient temperatures different from the temperatures in said main conduit, said bellows being expansible and contractible in accordance with variations of air pressure in said conduit and filled with a first fluid having substantially zero coefficient of thermal expansion so that its expansion and contraction are independent of the temperature in said chamber, a bulb in said main air conduit filled with a second fluid having a substantial coefficient of thermal expansion, a pressure transmitting connection between the interiors of said bulb and bellows so that the expansion of the second fluid in said bulb tends to produce expansion of said bellows and thereby modifies the position of said valve in accordance with the temperature in said main conduit, and means responsive to said air flow measuring means for controlling the flow of fuel to said engine proportional to said mass air flow.

7. Apparatus for regulating the flow of a liquid in proportion to the flow of a fluid of variable density, comprising a conduit for said fluid, means associated with said conduit for producing two unequal pressures whose difference is a function of the velocity of the fluid flowing thru said conduit, regulating means responsive to the difference of said pressures, a control device for compensating the action of said regulating means in accordance with the variations of pressure and temperature of the fluid in said conduit, a flexible bellows for operating said control device, a chamber for containing said bellows spaced from said conduit so that said bellows will not restrict said conduit, a passage connecting said chamber and said conduit, said chamber having walls subject to ambient temperatures different from the temperatures in said conduit, said bellows being expansible and contractible in accordance with pressure variations in said chamber and filled with a first fluid having substantially zero coefficient of thermal expansion so that its expansion and contraction are independent of the temperature in said chamber, a bulb in said conduit filled with a second fluid having a substantial coefficient of thermal expansion, and a pressure-transmitting connection between the interiors of said bulb and bellows so that the expansion of the second fluid in said bulb tends to produce expansion of said bellows and thereby modifies the position of said control device in accordance with the temperature in said conduit.

8. Apparatus for regulating the flow of a liquid in proportion to the flow of a fluid of variable density, comprising a main conduit for said fluid, means associated with said conduit for producing two unequal pressures whose difference is a func-

tion of the velocity of the fluid flowing thru said conduit, a secondary conduit connecting two points in said main conduit subject to said two unequal pressures so that a flow of fluid is induced thru said secondary conduit by the difference of said pressures, a chamber connected to said secondary conduit, a pair of restrictions in series in said secondary conduit, valve means for varying the cross-sectional area of one of said restrictions, a flexible bellows in said chamber for operating said valve means, said bellows being expansible and contractible in accordance with pressure variations in said chamber and filled with a liquid having substantially zero coefficient of thermal expansion, a bulb having rigid walls and placed in said main conduit above the uppermost part of said bellows, said bulb being filled with a fluid having a substantial coefficient of thermal expansion and substantially less dense than said liquid, a passage connecting the interiors of said bulb and bellows so that the expansion of the fluid in said bulb tends to produce expansion of said bellows and to adjust the position of said valve means and the fluid flow thru said secondary conduit is thereby modified in accordance with the pressure in said chamber and the temperature in said main conduit, and liquid flow regulating means responsive to the pressure drop established across the other of said restrictions.

9. A carburetor comprising a main air passage with a Venturi restriction therein, a secondary air passage from the inlet of the main air passage to said Venturi restriction, means, including a fixed restriction and a variable restriction in said secondary passage, for supplying fuel to said main air passage in proportion to the velocity of air flow therethru, means for compensating the fuel supply for variations in density of air flowing thru said main air passage comprising a bellows positioned in said secondary air passage which is insensitive to the temperature of the air and adjacent walls of said secondary air passage but is responsive to variations in air pressure therein and which is operatively connected to an element responsive to the temperature of the air at the inlet of said main air passage, and a valve actuated by said bellows for varying the size of said variable restriction.

10. A carburetor comprising an air passage with an air supply and a liquid fuel supply thereto, means for regulating the fuel supply in accordance with variations in density of the air supply, comprising a temperature control, responsive to the temperature but insensitive to the pressure of said air supply, and including a rigid sealed chamber suspended across the entrance to said air passage so as to be completely surrounded by the total air supply passing therethrough, and thereby insulated from the heat of said carburetor.

11. A carburetor comprising an air passage with an air supply and a liquid fuel supply thereto, means for supplying fuel to said air passage in proportion to the velocity of air flow therethrough, and means for compensating said fuel supply for variations in density of said air supply, including

an element, insensitive to ambient temperature changes, but responsive to the pressure of said air supply, operatively associated with an element responsive to the temperature of said air supply and insensitive to the pressure thereof.

12. A carburetor comprising a main air passage with a Venturi restriction therein, a secondary air passage from the inlet of the main air passage to said Venturi restriction, means, including a fixed restriction and a variable restriction in said secondary passage, for supplying fuel to said main air passage in proportion to the velocity of air flow therethrough, means for compensating the fuel supply for variations in density of air flowing through said main air passage comprising a bellows positioned in said secondary air passage and responsive to variations in air pressure therein and to the temperature of the air at the inlet of said main air passage, a sealed chamber located at the inlet of the main air passage, unaffected by the air pressure in said passage, and containing a temperature responsive fluid, a conduit connecting said chamber with said bellows, and a valve actuated by said bellows for varying the size of said variable restriction.

13. A carburetor according to claim 10, wherein said bellows is filled with a liquid having a zero coefficient of expansion and said chamber is filled with an expansible fluid having a relatively high coefficient of thermal expansion; said liquid and fluid being nonmiscible.

14. A carburetor according to claim 10, wherein said chamber is so located as to be completely surrounded and thermally insulated from the heat of the carburetor by the air passing through said main air passage.

15. A carburetor according to claim 10, wherein said chamber is filled with a gas and each end wall of said chamber is attached to the adjacent wall of said main air passage by a flexible connection, whereby said end walls are relatively movable with changes in temperature of said chamber.

MILTON E. CHANDLER.
